BRIDLE AND HACKAMORE BIT

Lou A. Burgess, Sasabe, Ariz.

Application February 25, 1943, Serial No. 477,115

8 Claims. (Cl. 54—6)

This invention relates to a combination bridle and hackamore bit.

It is particularly aimed to provide such a construction which may be used to apply pressure simultaneously on the nose, mouth and chin of the animal and a construction which may in the backamore form apply pressure on the nose, and such a form as may be readily changed over from driving to hackamore condition.

The more specific objects and advantages will become apparent from a consideration of the description following taken in connection with accompanying drawings illustrating an operative embodiment.

In said drawings:

Figure 1 is a view in side elevation showing the structure in side elevation and applied to a horse for driving purposes;

Figure 2 is a front elevation of the structure alone;

Figure 3 is a horizontal sectional view taken on the plane of line 3—3 of Figure 2;

Figure 4 is a detail section taken on the plane of line 4—4 of Figure 3;

Figure 5 is a top or plan view of the structure;

Figure 6 is a fragmentary section showing the use of a straight bit and taken approximately on the same plane as Figure 3; and

Figure 7 is a front elevation, partly broken away and in sections, showing the use of the structure as a hackamore bit.

Referring specifically to the drawings, wherein like reference characters designate like or similar parts, a pair of side plates 10 are employed against the outer surfaces of which a pair of levers 11 are disposed. Such parts are connected by a bit or mouth piece 12, for instance curved as at 13. This mouth piece has ends or terminal portions 14, reduced and providing shoulders 15. Portions 14 extend through openings 16 and 17 in the side plates and levers, respectively, and to fasten the parts together, nuts 18 are threaded on the outer portions of the reduced portions or shanks 14 and fastening pins or cotter keys 19 are preferably passed through openings in the nuts 18 and shanks 14. The side plates 10 turn on the shanks 14, while the levers 11 are connected to the shanks 14 so that the levers and mouth piece 12 will turn as a unit. To this end, the openings 16 are enlarged to provide diametric slots at 20 and shanks 14 have diametric slots 21 adapted to align therewith. Pins or couplings 22 are disposed in the slots 20 and 21, thus connecting the levers and mouth pieces for turning as a unit and the side pieces 10 for turning on the

mouth piece and relatively to the levers. All of the parts mentioned are detachable as will be understood.

Cheek straps 23 are detachably connected in enlarged slots or openings 24 at the top of the side pieces and a nose band 25 is detachably connected at opposite ends in openings or slots 26 of auxiliary levers 27 loosely pivoted at 28 on the outer surfaces of the side pieces 10. The levers 11 at 29 and auxiliary levers 27 at 30 have cam surfaces which are adapted to contact so that rotation of the levers 11 will rotate the auxiliary levers 27 to apply pressure or bind the nose strap 25 on the nose of the animal.

15 At the lower end of levers 11 they have openings or slots 31 so that eyelets 32 have a connecting link 33 may be fastened thereto, the length preferably being a single strand of wire to enable bending for application and removal.

20 The driving reins 34 are detachably connected in the openings 31 as shown. Forward movement of the upper ends of the levers 11 is limited by stops 35a fastened on the side pieces 10.

As a result of the construction described, it 25 will be seen that when the reins 34 are pulled, the movement of the levers 11 will result in turning of the mouth piece 12 to simultaneously apply pressure of the latter and the chin strap 35 is fastened in openings 36 on the levers, to the

30 animal and at the same time, the auxiliary levers 27 will be rocked on the pivots 28 through the coaction of cam surfaces 29 and 30 to apply pressure of the nose band 25 on the nose of the animal.

35 The structure is also adapted for use with a straight mouth piece 37 as well as with the curved mouth piece 12. When the straight mouth piece is used as in Figure 6, the curved mouth piece is removed and reduced screw threaded shanks 14a

40 of the straight mouth piece are applied through the openings 16 and 17 and fastened in place by the same nuts 18 and cotter keys or pins 19. The pins 22 however and slots 21 are omitted so that both the side pieces and levers 11 and mouth piece 37 may relatively turn.

The structure is also adapted for use as a hackamore bit as disclosed in Figure 7 in which event, mouth piece 12 is removed and short bolts 38 are passed loosely through each set of openings 50 16—17, being fastened in place by the aforesaid nuts 18 and cotter keys 19 passed through openings in the nuts 18 and bolts 38. Washers 20 are preferably interposed between levers 11 and nuts 18 in this form. The link 33 is not used but, instead, a chain 39 is fastened in openings 40 in

the levers 11 above the openings 31. In this form I also preferably use the nose band 25 fastened to the auxiliary side plates or levers 27, thus providing an automatic nose band feature in a hackamore bit.

Various changes may be resorted to provided they fall within the spirit and scope of the invention.

I claim as my invention:

1. A bit of the class described comprising side pieces, levers, a mouth piece passing loosely through the side pieces and connected for turning to the levers, a chin strap connected to the levers, and nose band means for pressure application through movement of the levers.

2. A bit of the class described having side plates, a mouth piece having portions extending loosely through the side pieces, levers with which said portions outwardly of the side pieces are connected for simultaneous turning, a chin strap connected to the levers and connections for a nose band carried by the side pieces and operable by the levers.

3. A bit of the class described comprising side pieces, a mouth piece having end portions extending loosely through the side pieces, levers outwardly of the side pieces connected to said portions for simultaneous turning therewith, connections for a nose band, said connections being mounted on the side pieces, and means to operate the connections through movement of the levers.

4. A bit of the class described having side pieces, a mouth piece having end portions passing loosely through the side pieces, levers having openings through which said end portions pass, and means interfitting with said openings and said portions to cause the levers and mouth piece to turn unitarily.

5. A bit of the class described having side pieces, a mouth piece having end portions passing loosely through the side pieces, levers having openings through which said end portions pass, and means interfitting with said openings and

said portions to cause the levers and mouth piece to turn unitarily, consisting of slots extending from the openings and slots in said portions, keys occupying said slots.

6. A bit of the class described having side pieces, a mouth piece having end portions passing loosely through the side pieces, levers having openings through which said end portions pass, and means interfitting with said openings and

10 said portions to cause the levers and mouth piece to turn unitarily, consisting of slots extending from the openings and slots in said portions, keys occupying said slots, auxiliary levers pivoted to the side pieces, said first mentioned levers and

15 auxiliary levers having coacting cam surfaces to move the auxiliary levers as the first mentioned levers are operated, a nose strap connected to the auxiliary levers.

7. A bit of the class described having side pieces, a mouth piece having end portions passing loosely through the side pieces, levers having openings through which said end portions pass, and means interfitting with said openings and

20 said portions to cause the levers and mouth piece to turn unitarily, consisting of slots extending from the openings and slots in said portions, keys occupying said slots, auxiliary levers pivoted to the side pieces, said first mentioned levers and auxiliary levers having coacting cam surfaces to

25 move the auxiliary levers as the first mentioned levers are operated, a nose strap connected to the auxiliary levers, a chin strap connected to the first mentioned levers, cheek strap connected to the side pieces and rein connections on the first mentioned levers.

8. A bit of the class described comprising side plates, levers disposed against the same, bolt means securing the plates and levers together, auxiliary levers pivoted on the side plates, said first mentioned levers and auxiliary levers having coacting cam surfaces, and a nose band connected to the auxiliary levers.

LOU A. BURGESS.
